KNIFE OR SIMILAR ARTICLE

Benoni Bureau, Elmhurst, N. Y.

Application March 14, 1949, Serial No. 1,383

Term of patent 14 years

(Cl. D22—3)

To all whom it may concern:

Be it known that I, Benoni Bureau, a citizen of the United States of America, residing in Elmhurst, county of Queens, and State of New York, have invented a new, original, and ornamental Design for a Knife or Similar Article, of which the following is a specification, reference being had to the accompanying drawing, forming part thereof.

Figure 1 is a side elevational view of a knife or similar article, showing my new design;

I claim:

The ornamental design for a knife or similar article, substantially as shown and described.

BENONI BUREAU.
